UNITED STATES PATENT OFFICE.

WARD GARRETT, OF GAYS, ILLINOIS.

BOTTLE-STOPPER FASTENER.

1,179,819.

Specification of Letters Patent.

Patented Apr. 18, 1916.

Application filed September 11, 1912. Serial No. 719,778.

To all whom it may concern:

Be it known that I, WARD GARRETT, a citizen of the United States, residing at Gays, in the county of Moultrie and State 5 of Illinois, have invented new and useful Improvements in Bottle-Stopper Fasteners, of which the following is a specification.

This invention relates to stopper fasteners for bottles, and one object of the invention is to produce a simple and efficient stopper fastener which may be readily applied to an ordinary bottle and which, by its presence, may be taken to indicate that the bottle 10 contains poison or other dangerous material.

15 A further object of the invention is to produce a simple and efficient stopper fastener which may be readily applied to an ordinary bottle and which will secure the stopper in such a manner that it may not be 20 readily removed especially forming a safeguard against removal of the stopper by young children.

With these and other ends in view which 25 will readily appear as the nature of the invention is better understood, the same consists in the improved construction and novel arrangement and combination of parts which will be hereinafter fully described and particularly pointed out in the claim.

30 In the accompanying drawing has been illustrated a simple and preferred form of the invention, it being, however, understood that no limitation is necessarily made to the precise structural details therein exhibited, 35 but that changes, alterations and modifications within the scope of the claim may be resorted to when desired.

In the drawing, Figure 1 is a perspective view showing the improved fastener applied 40 to the neck of a bottle and showing the fastening lever moved to a non-obstructing position. Fig. 2 is a perspective view showing the fastener applied to a bottle and the lever in obstructing position with respect to the 45 stopper. Fig. 3 is a top plan view showing the stopper fastener detached.

Corresponding parts in the several figures are denoted by like characters of reference.

The improved stopper fastener includes 50 a body portion or attaching member which is formed of a piece of spring wire by primarily bending or doubling the same so as to form side members 1, 2 having opposed semi-circular loops 3, 4 adapted to encircle 55 the neck of a bottle. The bent or doubled portion of the wire is bent upward to form

a loop 5 which is disposed in a plane substantially at right angles to the plane of the loops 3, 4, from which the said upwardly extending loop is also suitably spaced. One 60 of the side members, 1, forms an arm or bracket 6 extending laterally and outwardly with respect to the loop 3, a portion of said arm being bent upward to form a bracket 7 having a terminal hook 8. The free end 65 of the side member 2 is bent to form, adjacent to the loop 4, a hook 9 which may be hooked over the arm 6 of the side member 1.

An obstructing lever 10 formed of a piece of wire is provided at one end with an eye 70 11 pivotally engaging the loop 5 with which the said lever is connected, said lever being of such length that its free end may be engaged with the hook 8. The lever 10 is formed, intermediate the ends thereof, with 75 a flattened portion designated by P. One purpose of this is to provide a flat bearing surface which will engage the cork stopper (to be hereinafter referred to) without cutting into the same. Another purpose is to 80 increase the resiliency of the lever so as to permit the free end thereof to be placed more readily in or out of active engagement with the hook 8. Still another purpose of the flattened portion P is to produce a surface 85 on which the name of the manufacturer, a designation of the contents of the package or other information may be impressed or stamped.

The improved device, which is preferably 90 formed of steel or other resilient wire, may be readily applied to a bottle, jar or other receptacle by placing the neck of such receptacle between loops 3, 4, after which the hook 9 is engaged with the arm 6 for the 95 purpose of retaining the device securely in position, it being understood that the bottle or other receptacle shown at 12 is provided at the upper edge of its neck 13 with a flange or lip 14, whereby the stopper fastener will 100 be securely retained. When a stopper 15 is placed in the mouth of the bottle it may be securely fastened by positioning the lever 10 diametrically across the same and securing the free end of said lever in engagement 105 with the hook 8. The stopper will thus be safely retained in such a manner that it may not be easily removed by a young child, and the presence of the stopper fastener may of itself be taken as an indication that the 110 contents of the receptacle is not to be tampered with.

The improved stopper fastener is simple and inexpensive, and it may be readily manufactured in various sizes adapted to fit bottles, jars and other receptacles of various dimensions. It may be easily applied or removed and when in position it will constitute a safe and efficient stopper fastening device.

Having thus described the invention, what 10 is claimed as new, is:—

A device of the class described, comprising a piece of spring wire bent to provide a pair of side members formed with opposed semi-circular loops, said side members being 15 bent upwardly at a right angle and terminating in an integral loop, an integral arm formed upon one of said first named loops in

alignment with one of said side members, a bracket formed integrally upon said arm at right angles thereto, a terminal hook formed 20 upon said bracket on a level with said second named loop, an integral hook formed upon the other of said side loops, adapted to engage said arm, a lever having an eye linked upon the second named loop and adapted 25 to project into said first named hook, and a substantially flattened lip formed intermediate the ends of said lever.

In testimony whereof I affix my signature in presence of two witnesses.

WARD GARRETT.
